UNITED STATES PATENT OFFICE.

WILLIAM AUGUSTUS KILMER AND SANFORD SWANBUM, OF DE KALB, ILLINOIS,
ASSIGNORS TO AMERICAN STEEL & WIRE COMPANY, OF WORCESTER, MASSACHU-
SETTS, A CORPORATION OF NEW JERSEY.

REEL.

1,036,642.

Specification of Letters Patent. Patented Aug. 27, 1912.

Application filed June 28, 1909. Serial No. 504,497.

To all whom it may concern:

Be it known that we, WILLIAM AUGUSTUS KILMER and SANFORD SWANBUM, both of De Kalb, in the county of Dekalb and State of Illinois, have invented a new and useful Reel, of which the following is a full, clear, and exact description, reference being had to the accompanying drawings, forming part of this specification, in which—

10 Figure 1 is a perspective view of the reel, and Fig. 2 is a similar view, showing the coil or bundle of barbed wire wound on and secured to the reel; and Fig. 3 is a view on a smaller scale showing the reel collapsed.

15 Our invention is designed especially to provide a reel or spool for holding barbed wire fencing, although it may be used for holding other wire products. It has been the common practice in the art to reel the 20 barbed wire fencing as it is formed in the machine upon a reel or spool made of wood, having wooden end pieces and wooden connecting pieces on which the wire is wound. Wooden reels are clumsy in appearance and 25 their lack of strength has often resulted in serious trouble, for when a reel breaks the coil of barbed wire expands and makes a snarl which is difficult and sometimes dangerous to handle. Our invention overcomes 30 all these difficulties and provides a spool which is stronger, lighter and cheaper than the devices heretofore employed. It holds the wire fencing with greater security and altogether makes a stronger, more convenient 35 and more easily handled package for shipment to the consumer. These advantages are of practical importance and will be appreciated by those who are familiar with the difficulties experienced with the 40 devices which have been employed heretofore.

The drawings show the preferred construction of our reel or spool and we will now describe it, premising that those skilled 45 in the art may modify it in various ways within the scope of the invention as defined in the following claims.

The reel shown in the drawings has two end pieces B, B made of metal wires or 50 strips (which we designate generically by the term wires), connected by cross pieces C, C. Each end piece B, B is preferably made of a single piece of wire, which is bent into trussed form, the general form prefer-

ably being that of an elongated ellipse, the 55 middle portion of which, on opposite sides, is bent inward, forming interengaging loops 2, 2 which lie in conjunction with one another and present a single eye for the insertion of a hollow arbor and pin when the 60 spool is applied in a wire barbing machine. The invention is, of course, not limited to making the end pieces B of single pieces of wire. The ends of the piece B when made of a single piece of wire are looped or 65 welded together, as at 3, thus holding the end pieces firmly together. This construction is especially desirable because it has considerable elasticity, and as the reels are subjected to rough handling, often being 70 thrown from railway cars to the platforms, such elasticity renders them less liable to break. The elongated construction of the end piece also gives a trussed effect which contributes greatly to the strength. 75

The cross-pieces C, C are preferably single strands of wire coiled at the ends 4 around the end pieces, thus binding them together flexibly so that the entire reel, before it is put into use, can be turned into a flat condition, as illustrated in Fig. 3, and thus readily packed or stored, taking but little room. This overcomes a serious objection of the 80 wooden reels, which, on account of their bulky form, took up a large amount of room in the warehouse, it being necessary, in a large wire barbing factory, to keep such 85 reels in stock in very large numbers.

In winding the wire on the reel we support the reel upon a frame, preferably constructed as shown in and forming the subject matter of our divisional case, Serial No. 535,262, filed December 28, 1909, for a support for wire reels. 90

Our invention in its broader claims is not 95 limited to the collapsing feature of the reel, or to other features of construction, unless specifically recited in the several claims.

We claim:—

1. A reel for wire comprised of two end 100 pieces and cross connecting wires hinged thereto, each of said end pieces being formed from a single length of wire bent to outline two similar triangles, the bases of the triangles being opposed and separated by a circular eye formed from the connecting portions of the wire which outlines the triangles, substantially as described. 105

2. A reel for wire composed of two end pieces and cross connecting wires hinged thereto, each of said end pieces being formed from a single length of wire bent to outline two similar triangles, the triangles being connected by opposed U-shaped overlapping loops, whereby a circular eye for an arbor is formed, substantially as described.

In testimony whereof, we have hereunto set our hands.

WILLIAM AUGUSTUS KILMER.
SANFORD SWANBUM.
